United States Patent Office

Des. 207,720
Patented May 23, 1967

207,720

VIBRATORY SANDER OR SIMILAR ARTICLE

Nicholas T. Anton, Park Ridge, Ill., assignor to Wen
Products Inc., Chicago, Ill., a corporation of Illinois

Filed May 2, 1966, Ser. No. 2,107

Term of Patent 14 years

(Cl. D37—1)

Fig. 1

Fig. 2

*Fig. 3**Fig. 4*FIGURE 1 is an isometric view of a vibratory sander or similar article embodying my new design;

FIGURE 2 is a side elevation thereof;

FIGURE 3 is a top plan view thereof; and

FIGURE 4 is a rear elevation thereof.

The undisclosed bottom portions are unornamented. The dominant features of my design reside in the portions shown in full lines.

I claim:

The ornamental design for a vibratory sander or similar article, as shown and described.
